YIELDABLE PRESSURE APPLYING CLAMP

James A. Watt, Chicago, Ill.

Application July 7, 1938, Serial No. 217,872

7 Claims. (Cl. 24—255)

This invention relates to a clamp and more particularly to a yieldable pressure applying clamp especially adapted for use in clamping fragile material, such, for example, as curtains, hosiery, film, and many other such articles.

An object of this invention is to provide an improved clamp in which provision is made for limiting the amount of clamping pressure that can be applied to an article so as to prevent marring of the article by reason of excessive pressure being applied thereto.

Another object of this invention is to provide a clamp which may be readily attached to or suspended from any suitable support and which can be tightened into tight cooperation with the material to be clamped without leaving any objectionable indentation or mar in the material.

Still another object of the invention is to provide an improved clamp which is simple and which lends itself to economical manufacture on a large production basis.

In accordance with the general features of this invention, there is provided a clamp for fragile material and the like comprising opposed clamping jaws connected by tightening means disposed between the extremities of the clamp and manually operative to force the clamping ends of the jaws at one side of the tightening means into clamping engagement with the material and being provided with resilient cushioning means at the other side of the tightening means so tensioned as to be automatically displaceable upon excessive tightening of the tightening means to permit the other ends of the jaws on said opposite side to move toward each other and thus relieve the clamped material from the application of any further or damaging pressure.

Another feature of the invention relates to the forming of the material engaging surfaces of the jaws of a rubber material which is relatively harder than the cushioning means, so that the cushioning means of the clamp will be displaceable much more readily than the rubber material actually in contact with the article clamped.

Still another feature of the invention relates to offsetting the clamping extremities of the clamp so as to cause these extremities to be substantially parallel to each other when the clamp is closed whereby the clamp has a surface engagement with the clamped material rather than merely a line contact.

A further feature of the invention relates to the provision of means for attaching the clamp to a support which means does not interfere with the operation of the clamp and which may take

a number of different forms such as an eyelet, a mounting screw, or a suction cup.

Other objects and features of this invention will more fully appear from the following detailed description taken in connection with the accompanying drawing which illustrates several embodiments thereof, and in which:

Figure 1 is a side view of one form of my clamp showing it applied to material to be clamped;

Figure 2 is a front view of the clamp showing in section the cushioned end thereof and illustrating the clamp in its open position;

Figure 3 is a view similar to Figure 2 but showing the clamp closed and in clamping engagement with material;

Figure 4 is a view similar to Figure 3 illustrating how the cushioning rubber is displaced upon the tightening of the clamp to a point beyond that necessary to effect clamping engagement with the material held thereby;

Figure 5 is a side view similar to Figure 1 of a modified form of clamp;

Figure 6 is a view similar to Figure 2 of the front of the clamp of Figure 5, partly in section, and showing the clamp in engagement with material clamped therebetween and also illustrating the cushioning rubber as being displaced by reason of the tightening of the clamp to a point beyond that necessary to effect the desired clamping action;

Figure 7 is a side view of still another form of clamp showing it applied to material; and

Figure 8 is an end view of the clamp shown in Figure 7, partly in section, and illustrating the action of the clamp.

As shown on the drawing:

The reference characters 10 and 11 designate two substantially parallel clamping strips which, when the clamp is in open position, are substantially spaced apart and in substantial parallelism, with the exception that the clamping ends 12 and 13 of these strips. It will be perceived that the two clamping ends of these jaws or strips are offset laterally so that these two ends may be properly characterized as diverging ends. The reason for this is so that when the clamping ends are brought into clamping position as shown in Figure 3, their contact surfaces will be in substantial parallelism. If it were not for this feature, the ends of the clamping device would only have substantially a line contact. The use of this feature, however, enables the clamping extremities of the two jaws 10 and 11 to have a very substantial surface engagement with the material 9 clamped therebetween.

Also, I have found it desirable, when this clamp is intended for use with fragile material, although it is of course evident that it has other applications, to provide the facing surfaces of the two ends 12 and 13 with rubber facings 14 and 15. The rubber used in these facings, however, is relatively harder than the rubber used in the spacer 16 at the other side of the clamp, which I will now proceed to describe.

10 This spacer or cushioning device 16 may be made of any suitable material, but I have found the best results are obtained by making it of soft rubber, such, for example, as crepe or gum rubber. This feature is advantageous in that the spacer 16 will be displaced before there is any substantial displacement of the rubber facings 14 and 15 when the clamp is tightened into cooperation with the material 9.

20 The rubber 16 is illustrated as being tubular and it is mounted on a ferrule or sleeve 17 which may be made of any suitable material, such, for example, as metal.

25 The ends of this sleeve or elongated eyelet are clinched over the outer sides of the strips 10 and 11 as indicated at 18 and 19 so as to limit outward separation of the two strips 10 and 11 and so as to hold the device in assembled condition.

30 One advantage of using a tubular connecting member for connecting the two strips 10 and 11 and for holding the cushioning device 16 in place is that this tubular member 17 may also be used to mount the clamping device on a suitable support, such, for example, as a hook or the like.

35 Located in an intermediate position, relative to the length of the clamp, is a tightening device or screw 20 which is threaded at one end to receive a tightening cap 21 screwed thereon and is threaded and formed into a screw 22 at its other end, which may, if it is so desired, be used instead of the eyelet 17 to attach the clamping device to a wall. Also threaded upon the end 22 of the tightening device 20 is a nut 23 against which pressure is applied when the cap or nut 21 is turned for the purpose of moving the clamping jaw or strip 11 toward the strip 10 and into clamping position, as shown in Figure 3.

40 50 The operation of this clamp is, briefly, as follows: Normally, when the clamp is in open position, the two clamping strips or jaws 10 and 11 are substantially parallel to each other, as shown in Figure 2. Upon the tightening of the cap or nut 22 to dispose the clamp in clamping engagement with material 9, the ends 12 and 13 of the clamping strips on one side of the tightening device are brought together, as shown in Figure 3, with the rubber facings 14 and 15 in substantial surface engagement with the material 9.

45 55 The material of the cushioning device is so tensioned that upon the application of a predetermined or excessive amount of tightening pressure to the two strips 10 and 11, the rubber 16 will yield so as to prevent the clamping jaws from marring or forming an indentation in the material and thus damaging the same. This action is illustrated in Figure 4. In other words, during the tightening of the clamp and upon a point being reached where the resistance to further drawing in of the ends 12 and 13 is greater than that afforded by the cushioning device 16, this device will yield and will allow

5 the opposite or upper ends of the clamping device to fulcrum about the central tensioning device. In reality, what happens is that the upper end of the strip 11 pivots or is moved along the sleeve 16 towards the upper end of strip 11. This results in the displacement of the rubber comprising the spacer 16.

10 Thus it will be perceived that I have provided a clamping device with an intermediate tightening means so related to the opposite extremities of the clamping device that initially the clamping ends of the device will be drawn inwardly toward the material upon the tightening of the device into clamping engagement and thereafter after a predetermined amount of pressure has been applied the opposite ends of the device will be caused to be moved toward each other so as to prevent an excessive amount of pressure from being applied to the material being clamped. To open the device all that is necessary is to turn the cap or nut 21 on the tensioning element 20. Of course, as soon as the pressure of this tightening device is relieved, the natural resiliency of the rubber spacer 16 will function to spread the legs or strips 10 and 11 apart and out of engagement with the material 9 embraced by the free ends of the clamp.

15 20 25 In Figures 5 and 6, I have illustrated a modified form of clamp similar to the one shown in the first four figures but differing principally therefrom in that a rubber suction cup 22' is substituted for the screw and nut 22 and 23 of the first form of the invention. The numerals 10' to 21' inclusive designate parts of the clamp which correspond substantially with parts 10 to 21 inclusive of the first described form of the invention. It will be perceived that the tightening element 20' has a head 23' embedded in the molded suction cup 22'.

30 35 40 In the use of this clamping device, the operation is substantially the same as that of the first described form. Obviously, once the suction cup 22' is pressed down into clamping engagement with a smooth surface of a suitable support, the nut or cap 21' may be tightened or loosened without interfering with the support afforded by the suction cup. It should also be noted that in pressing the suction cup into holding cooperation with the surface, the pressure is transmitted from the cap directly to the cup and not through the material held by the clamp.

45 50 55 60 65 In Figures 7 and 8, I have illustrated still a further modification of the invention, in which I have substituted substantially circular plates for the elongated clamping strips of the first two forms of the invention. These plates are designated by the reference characters 10a and 11a. These two plates are substantially circular, with the exception that the clamping plate 10a has a lateral extension 10c which is apertured at 10d so that this extension may be used to support the clamp on a suitable hook or other similar medium.

70 75 80 85 At this time, it should be noted that in all forms of the invention, the clamping elements or jaws, namely, the strips 10 and 11, 10' and 11', and 10a and 11a, may be made of any suitable rigid material, such, for example, as metal, a phenolic condensation product, wood, or any substance of less resiliency than the cushioning medium or spacer. Of course, if it is

so desired, such substance may be suitably reinforced by inserts, backing or the like.

Each of the two plates 10a and 11a has a rubber facing which is in the form of a rubber annulus and which is designated by the reference numerals 14a and 15a. This rubber facing may be secured in any suitable manner to the plate and is preferably made of a soft rubber, such, for example, as crepe rubber.

10 The two clamping plates 10a and 11a are held in cooperation with each other by a tightening element 20a having both of its ends threaded, and having threaded on one end a tightening nut 21a and on its other end a stop nut 23a. 15 It will also be perceived that one of the threaded ends of this element 20a is formed into a screw 22a which may, if desired, be used to attach the clamping device to a suitable support, such, for example, as a wall, a window frame, or the like.

Upon tightening of the clamp into engagement with the material 9, it will be noted from Figure 8 that one side of the clamping device embraces the material, whereas at the other side the rubber facings are in engagement with each other. As a consequence thereof, it follows that the thickness of the material between the two clamping elements or members on one side of the tightening device will result in the cocking 20 of the plate 11a with respect to the plate 10a. Moreover, after a predetermined amount of pressure has been applied to the material 9 sufficient to overcome the resistance afforded by the mass 25 of rubber facings, these rubber facings will yield so as to prevent an excessive amount of pressure being applied to the material and thus damaging the material clamped.

From the foregoing, it is apparent that I have provided a simple clamp which is especially 40 adapted for use in connection with fragile material, such, for example, as curtains, stockings, film and numerous other articles of like character. One application of the clamp which I have found to be particularly useful is where the 45 clamp is used as a means for tying a curtain to a window frame so as to prevent the curtain from flying into the room and against a screen due to currents of air entering the open window. Another excellent use to which my clamp may 50 be put is for the purpose of holding up fragile clothing and particularly women's attire, such as undergarments, stockings and the like, after such garments have been washed. The yieldable feature of the intermediate cushioning device, 55 of course, functions at all times to prevent an extensive amount of clamping pressure from being applied to the material engaged so that no indentations or other mars are left in such material by the clamping device.

60 I am aware that many changes may be made and numerous details of construction may be varied through a wide range without departing from the principles of this invention, and I, therefore, do not purpose limiting the patent granted 65 hereon otherwise than necessitated by the prior art.

I claim as my invention:

1. A clamp comprising opposed clamping jaws, 70 tightening means disposed between the extremities of the clamp and manually operative to force clamping ends of said jaws at one side of said tightening means into clamping engagement with the material to be clamped, resilient cushioning means at the other side of said tightening means 75 opposite from said clamping side and so tensioned as to be automatically displaceable upon further tightening of said tightening means to permit the other ends of said jaws at said other and opposite side to move towards each other and thus relieve said clamped material from excessive and damaging clamping pressure, said cushioning means comprising resilient spacing means interposed and held between said other ends of said jaws.

2. A clamp comprising opposed clamping jaws, 10 tightening means disposed between the extremities of the clamp and manually operative to force clamping ends of said jaws at one side of said tightening means into clamping engagement with the material to be clamped, resilient cushioning means at the other side of said tightening means 15 opposite from said clamping side and so tensioned as to be automatically displaceable upon further tightening of said tightening means to permit the other ends of said jaws at said other and opposite side to move towards each other and thus relieve said clamped material from excessive and damaging clamping pressure, said cushioning means comprising resilient spacing means interposed and held between said other ends of said jaws.

20 2. A clamp comprising opposed clamping jaws, tightening means disposed between the extremities of the clamp and manually operative to force clamping ends of said jaws at one side of said tightening means into clamping engagement with the material to be clamped, resilient cushioning means at the other side of said tightening means 25 opposite from said clamping side and so tensioned as to be automatically displaceable upon further tightening of said tightening means to permit the other ends of said jaws at said other and opposite side to move towards each other and thus relieve said clamped material from excessive and damaging clamping pressure, said cushioning means comprising a relatively soft rubber spacer interposed between said other ends of said jaws.

3. A clamp for fragile material and the like comprising opposed clamping jaws, tightening means disposed between the extremities of the clamp and manually operative to force clamping ends of said jaws at one side of said tightening means into clamping engagement with the material to be clamped, resilient cushioning means at the other side of said tightening means 30 opposite from said clamping side and so tensioned as to be automatically displaceable upon further tightening of said tightening means to permit the other ends of said jaws at said other and opposite side to move towards each other and thus relieve said clamped material from excessive and 35 damaging clamping pressure, said cushioning means comprising a relatively soft rubber spacer interposed between said other ends of said jaws, said clamping ends of said jaws having their opposed material engaging surfaces formed of 40 rubber having harder characteristics relatively to 45 said rubber spacer.

4. A clamp for fragile material and the like comprising opposed clamping members, means for tightening the members into contact with the material to be clamped, cushioning means associated with said members and said tightening means so as to be stressed by the tightening of 50 said members into clamping position and effective thereafter upon further tightening of the 55 members to relieve said material from any excessive and damaging pressure, said clamping members comprising a pair of opposed disks with said tightening means disposed centrally and transversely thereof.

5. A clamp for fragile material and the like comprising opposed clamping members, means for tightening the members into contact with the material to be clamped, cushioning means associated with said members and said tightening means so as to be stressed by the tightening of 60 said members into clamping position and effective thereafter upon further tightening of the members to relieve said material from any excessive 65 and damaging pressure, said clamping members comprising a pair of opposed disks with said tightening means disposed centrally and transversely thereof, one of said circular disks being provided with an extension formed to serve as a 70 75

support for attaching the clamp to a wall or the like.

6. A clamp for fragile material and the like comprising opposed clamping jaws, tightening means disposed between the extremities of the clamp and manually operative to force clamping ends of said jaws at one side of said tightening means into clamping engagement with the material to be clamped, resilient cushioning means at the other side of said tightening means opposite from said clamping side and so tensioned as to be automatically displaceable upon further tightening of said tightening means to permit the other ends of said jaws at said other and opposite side to move towards each other and thus relieve said clamped material from excessive and damaging clamping pressure, said cushioning means being connected to said other ends of said jaws by means upon which said other ends may slide inwardly toward each other, said connecting means being tubular so as to constitute an elongated eyelet by means of which the clamp may be extended from a suitable support.

7. A clamp for fragile material and the like comprising opposed clamping jaws, tightening means disposed between the extremities of the clamp and manually operative to force clamping ends of said jaws at one side of said tightening means into clamping engagement with the material to be clamped, resilient cushioning means at the other side of said tightening means opposite from said clamping side and so tensioned as to be automatically displaceable upon further tightening of said tightening means to permit the other ends of said jaws at said other and opposite side to move towards each other and thus relieve said clamped material from excessive and damaging clamping pressure, said clamping jaws comprising two strips having outwardly offset and diverging end portions at the clamping ends of said jaws which portions are arranged to be brought into substantial parallelism when the clamp is closed into a clamping position so as to have a substantial engagement with the clamped material.

JAMES A. WATT.
